(57) **CLAIM**

The ornamental design for a mount assembly for exterior lamp as shown and described.

DESCRIPTION

FIG. 1 is rear elevation view of the mount assembly for exterior lamp in accordance with the present design;
FIG. 2 is a left side elevation view of the present design;
FIG. 3 is a right side elevation view of the present design;
FIG. 4 is top plan view of the present design;
FIG. 5 is bottom plan view of the present design;
FIG. 6 is a front perspective view of the present design shown disassembled;
FIG. 7 is a rear perspective view of the present design shown disassembled;
FIG. 8 is a front perspective view of the present design; and,
FIG. 9 is a rear perspective view of the present design. The portions shown in broken lines are for illustrative purposes only and form no part of the design.
